UNITED STATES PATENT OFFICE.

SAMUEL W. PRIEBE, OF WYACONDA, MISSOURI.

FRAME FOR STACKING GRAIN.

Application filed October 8, 1921. Serial No. 506,455.

To all whom it may concern:

Be it known that I, SAMUEL W. PRIEBE, a citizen of the United States, and resident of Wyaconda, county of Clark, and State of Missouri, have invented new and useful Improvements in Frames for Stacking Grain, of which the following is a specification.

This invention relates to an improvement in frames for stacking grain and the object is to provide a suitable housing for a stack of hay, straw or the like, for the purpose of protection against the wind and other elements.

15 The frame is particularly adapted for use in connection with pneumatic stackers and is composed of sections which may be assembled as the stack of straw or hay fills the sections initially constructed in the formation of the stack.

20 The invention consists of a plurality of metallic posts and a plurality of frames or panels, which panels are removably connected to the various posts in forming the 25 housing for the straw.

The posts are first erected and suitably braced, and then a row, or several rows of panels are attached to the post as the occasion warrants and as the stack begins to 30 grow due to the filling of the enclosure with the straw additional sections are applied. After the stack has been completed and the various sections applied thereto the braces are removed. The several sections 35 of panels which are connected to the posts giving the desired rigidity to produce a stable structure.

The invention consists of certain novel features of construction and combination of 40 parts which will be hereinafter described and pointed out in the claims.

In the accompanying drawings:

Figure 1 is a perspective view of the assembled stacker;

45 Figure 2 is a top plan view showing a number of sections in place.

Figure 3 is an end view;

Figure 4 is a view in perspective showing the details of construction and the manner 50 of attaching a side and end section;

Figure 5 is a detail view in elevation showing a corner post provided with an extension;

Figure 6 is a view in elevation of a portion of one of the intermediate posts; 55

Figure 7 is a perspective view of an extension in topping the stack; and

Figure 8 is a view in elevation of an intermediate post with extension.

The sections or panels are preferably 60 made up of rectangular frames, and over these frames are stretched and fastened a suitable covering, such as wire netting, or canvas, or metal plates.

Corner posts A and intermediate posts B 65 are made up of angle iron, and arranged at suitable intervals throughout the length of the posts A and on two adjacent sides thereof are hooks 2 and 3, respectively, while the posts B are provided with hooks 4. The 70 hooks are preferably pivoted to the posts although they may be made rigid. Each post is provided at its base with a brace 5, which is pivotally attached to the post. On the corner posts A, an auxiliary brace 6 is 75 pivotally connected to the posts, above the pivotal connection of the brace 5, and located at right angles to the brace 5, but on the intermediate posts B the brace 6 is 80 located opposite to the brace 5. A bar 7 is 85 pivotally connected to the brace 6 near its lower end and is adapted to be connected to the posts A or B by means of bolts 8 passing through one of the several openings 9 formed in the posts, thereby affording a 90 suitable bracing for the posts at their base whereby they may sustain the weight of the panels supported thereon.

In assembling the stacker or housing, the posts are set up and braced by means of braces 10, as shown in Figure 4, which braces are removed after the stacker has been assembled. Then the first row of panels C are attached to the posts by resting them on the braces 6 of the posts, and attaching them to the posts by means of hooks 11 on the corner posts A, and hooks 12 of the posts B. The second row of panels C are located on the outside of the posts and are supported by means of hooks 3 on the posts A and hooks 4 of the posts B. 95

The end panels D are all located on the exterior of the posts and are supported thereon by means of the hooks 2. It is to be noted that in supporting the panels C and D on the posts, that after the first row has 100 105

been applied, the panels are supported both at their upper and lower longitudinal edges by means of the hooks 3, 4 and 2.

The front posts of the stacker or housing 5 are preferably shorter than the rear posts, and therefore in building the stacker, perhaps two rows of panels C, and end panels D, will be attached to the posts, and only one row of panels C to the front posts. In 10 this way, it is found more satisfactory to build the stack, as the stacking machine is generally located adjacent the short or front posts, so that it is easier to deliver the straw to the stacker. As the stacker or 15 housing begins to fill additional panels will be applied, and then the extensions 13 will be attached to the corner posts, and the extensions 14 to the intermediate posts.

These extensions are provided with an 20 angle iron clip 15 which is spaced from the lower end of the extension, so that the upper end of a post may be slipped between the lower end of the extension and the clip 15. The extensions are provided 25 with hooks for supporting the panels, and are designated 2 and 3 for the corner extensions and 4 for the intermediate post extensions.

When the stacker or housing is filled, the 30 posts are provided, that is, the posts on the rear side of the stacker, with inclined extensions 16, as shown in Figures 3 and 7, whereby the last row of panels, which are attached to the hooks 17 thereof, will over- 35 lie the top of the stack and protect it from the wind and weather. The number of extensions employed is governed by the height of the stack.

If a round stack is to be constructed, then the intermediate posts B are eliminated 40 and only the corner posts are employed.

Having described my invention, what I claim as new, and desire to secure by Letters Patent is:

1. A frame for stacking grain, including 45 a plurality of portable posts, rectangular frames engaging said posts and arranged in rows, the ends of said frames overlapping at each post, and means on the posts for removably supporting and engaging the overlapping ends of the frames.

2. A frame for stacking grain, including 50 a plurality of posts, rectangular and side frames, means for supporting the end frames on the posts, the ends of the adjacent side frame overlapping, and means for removably supporting the side frames on the posts and engaging the overlapping ends.

3. In a frame for stacking grain, the combination of a plurality of posts and 60 covered panel frames to be applied and supported by the posts, means for removably supporting the panel frames on the posts, said frames adapted to be applied to the posts and engaged by said supporting 65 means as the stacker frame is filled.

4. The combination of a collapsible frame 70 for stacking grain, including a plurality of posts and rows of covered panel frames, and means for removably supporting the panel frames on the posts, a row of said panel frames being applied to the posts at the base along their inner surfaces, and additional rows applied to the exterior of said posts as the frame is filled with grain.

SAMUEL W. PRIEBE.
